UNITED STATES PATENT OFFICE.

HENRY K. PORTER, OF BOSTON, MASSACHUSETTS.

WHIFFLETREE-IRON.

SPECIFICATION forming part of Letters Patent No. 394,209, dated December 11, 1888.

Application filed February 17, 1888. Serial No. 264,323. (No model.)

To all whom it may concern:

Be it known that I, HENRY K. PORTER, of Boston, in the county of Suffolk and State of Massachusetts, have invented a new and useful Improvement in Whiffletree-Irons, which will, in connection with the accompanying drawings, be hereinafter fully described, and specifically defined in the appended claims.

In said drawings, Figure 1 is a plan view of the inner side of one of the supporting irons or straps. Fig. 2 is an edge elevation of said supporting-irons. Fig. 3 is a plan view of the outer side of one of said supporting-irons. Fig. 4 is a front elevation showing the central portions of the cross-bar and whiffletree and the irons by which the latter is connected with and supported by the cross-bar. Fig. 5 is a top plan view of the central portion of the whiffletree and its pivoting-iron. Fig. 6 is a sectional elevation, the section through the whiffletree being central, as on line Z Z, Figs. 1, 3, 4, and 5, while the section through the cross-bar is at one side of the center. Fig. 7 shows a modification of the supporting-irons.

My invention relates to the irons by which the whiffletree of express-wagons and other one-horse vehicles is supported from the cross-bar, and is pivotally connected with said supporting-irons; and it consists in features of novelty hereinafter fully described, and pointed out in the claims.

Referring again to the drawings, A represents the cross-bar, which at its ends is secured to the shafts in front of the forward axle, and B represents the whiffletree, which is pivotally supported by the cross-bar, through the agency of supporting-irons, in front of said cross-bar. A lower or bottom supporting-iron is shown at C and a like upper iron at D, these irons being secured to the cross-bar by bolts c, which pass through holes a b, respectively formed in said irons. Said irons differ only in that iron C has square holes a for the square part of bolts c, while iron D has round holes b to receive the round portion of said bolts, and either of said irons may be arranged on top of the cross-bar, as may be preferred. At their front ends said irons are preferably formed with a re-enforce or thickening, as d, while on their inner faces are formed the short tubes or hollow tapering

bosses g, through which, as well as through the entire supporting-iron, extends the coincident axial holes e for the reception of bolt h.

The pivoting-iron E of the whiffletree is formed with the front plate, i, having a central tubular enlargement, j, with the inwardly-tapering passage k to receive bosses g, and also having holes to receive the securing-bolts m, as shown. Said iron E has also the integral wearing-plates l, which at their rear ends may be secured to the whiffletree by screws f, as shown in Fig. 5.

As shown in Fig. 6, the bosses g extend from the faces of irons C D just far enough to allow iron E and the whiffletree to vibrate with due freedom, when the meeting faces of said bosses are brought into rigid contact by screwing up the nut on bolt h, said bosses thus forming the pivot for iron E, and irons C D, through said bosses and bolt h, being rigidly locked together to prevent motion or consequent wear thereof.

In Fig. 7 the re-enforce d is shown as formed separate from the supporting-iron and as having tube g formed upon it and extending through a hole in the iron, while a stud, n, also formed on re-enforce d, is inserted in a hole in the supporting-iron to hold the re-enforce and its boss from rotation from any cause; but such change in construction not only embodies the essential features of my invention, but is an obvious change or modification, deemed by me as inferior in point of efficiency to the construction shown in Figs. 1, 2, 4, and 6, where the supporting-iron, the re-enforce, and hollow boss are integrally formed.

I am aware that supporting-irons having a shallow hollow cord formed upon them to enter a corresponding depression in the pivoting-iron of the whiffletree have heretofore been used and discarded by reason of the objection which I avoid—to wit, that the nut on bolt h could not be screwed up solid, so as to serve as a “locking-nut,” and hence all the parts were comparatively loose, and therefore susceptible to vibration, wear, and rattling, thus accelerating their wearing out.

If at any time by long use and wear the whiffletree-iron E should acquire too free play between irons C D, the meeting faces of bosses g may be filed down sufficiently to render iron

E as close-fitting as is requisite, the taper of bosses *g* causing them to fit more closely as they are advanced into iron E. In fact the bosses *g* may be slightly shorter than shown, 5 with one or more disks of thin metal interposed between their meeting faces, so that by removing one or more of said disks the irons C D may be brought closer together when desired; but I deem it preferable, for obvious reasons, to have said bosses abut directly against each other, as shown. I claim as my invention—

1. The combination, with pivoting-iron E, formed with passage *k* therethrough, of supporting-irons C D, having respectively the 15 porting-irons *C D*, having respectively the hollow bosses *g g* of a length to extend through iron E and abut against each other, substantially as specified.
2. The combination of supporting-irons C

D, formed with hollow tapering bosses *g*, and 20 pivoting-iron E, formed with passage *k*, corresponding to said bosses, substantially as specified.

3. The pivoting-iron E, formed with front plate, *i*, tubular portion *j*, extended across 25 plate *i*, and wearing-plates *l*, all as an integral casting, substantially as specified.

4. The combination of pivoting-iron E, having the inwardly-tapering passage *k*, supporting-irons C D, having tapering hollow bosses 30 *g* fitting and meeting in said passage, and screw-bolt *h*, passing through said bosses to lock said parts together, substantially as specified.

HENRY K. PORTER.

Witnesses: HENRY HUNT LETTENNEY, EUGENE HUMPHREY.
